DISPENSING CAP FOR CONTAINERS

José María Bernabó and Hernan Bernabó,
Buenos Aires, Argentina

Application January 27, 1953, Serial No. 23,324

Term of patent 14 years

(Cl. D58—26)

To all whom it may concern:

Be it known that we, José María Bernabó and Hernan Bernabó, citizens of Argentina, whose residence is Terrado 2346, Buenos Aires, Argentina, and whose post-office address is Terrado 2346, Buenos Aires, Argentina, have invented a new, original, and ornamental design for a Dispensing Cap for Containers, of which the following is a specification, reference being had to the accompanying drawing, forming a part hereof.

Fig. 1 is a top perspective view of a dispensing cap for containers showing my new design;

Fig. 2 is a top plan view thereof;

Fig. 3 is a perspective view looking from the bottom of the container.

We claim:

The ornamental design for a dispensing cap for containers, as shown.
